UNITED STATES PATENT OFFICE

160,220

COMBINED PERFUME CONTAINER AND
GLOVE HOLDER

Victor Silson, New York, N. Y.

Application February 4, 1950, Serial No. 7,739

Term of patent 3½ years

(Cl. D86—10)

To all whom it may concern:

Be it known that I, Victor Silson, a citizen of the United States of America, residing in New York, county of New York, and State of New York, have invented a new, original, and ornamental Design for a Combined Perfume Container and Glove Holder, of which the following is a specification, reference being had to the accompanying drawing, forming part thereof.

Fig. 1 is a front view of a combined perfume container and glove holder showing my new design.

Fig. 2 is a side view thereof.

Fig. 3 is a perspective view showing the container slightly raised prior to insertion of the gloves in the bottom loop formed by the chain and base of the container.

I claim:

The ornamental design for a combined perfume container and glove holder substantially as shown and described.

VICTOR SILSON.
